UNITED STATES PATENT OFFICE.

CHARLES C. TOMKINSON, OF PLAINFIELD, NEW JERSEY.

CLOTHES WRINGER.

1,411,983.

Specification of Letters Patent.

Patented Apr. 4, 1922.

Application filed September 27, 1919. Serial No. 326,775.

To all whom it may concern:

Be it known that I, CHARLES C. TOMKINSON, a citizen of the United States, and a resident of Plainfield, Union County, and 5 State of New Jersey, have invented certain new and useful Improvements in Clothes Wringers, of which the following is a specification, reference being had to the accompanying drawings, forming a part thereof. 10 This invention relates to clothes wringers, and its object is to provide a simple and effective arrangement for preventing the clothes from wrapping around the rollers. Another object is to so arrange the parts that 15 the wringer may be operated in reverse directions.

These and other objects of the invention will appear in the following specification in which I will describe the invention and the 20 novel features of which will be set forth in appended claims.

Referring to the drawings:

Figure 1 is a front elevation of an apparatus which is made according to and embodies this invention; a part is broken away 25 and represented in section to more clearly show the construction.

Figure 2 is an end elevation of the apparatus.

30 Figure 3 is a sectional end elevation of the apparatus, this section being taken on the lines 3—3 of Figure 1.

Figure 4 is a sectional front elevation of a part of the apparatus and illustrates a 35 modified form of construction.

Like characters of reference designate corresponding parts in all the figures of the drawings.

10 designates the frame of the wringer. 40 11 is the lower roller, the shaft of which is mounted in fixed bearings in the frame.

12 is the upper roller, the shaft of which is mounted in bearing blocks 13 vertically 45 movable in the frame and pressed down- wardly by adjustable springs 14.

15—15 are feed and discharge boards affixed to the frame near and on opposite sides of the rollers.

20 is a brush which is parallel with and 50 centrally located above the upper roller, which is affixed to the frame 10 on angle irons 21 through which pass threaded studs 22 from the back of the brush. Nuts 23 complete this attachment and provide means 55 for manually adjusting the position of the brush vertically.

At opposite sides of the roller 11 are similar brushes 25—25 parallel with and centrally disposed in relation to a horizontal plane through the axis of the brush. These 60 are rigidly secured to the frame 10 and to the inner ends of the boards 15.

It may be desirable to impart the vertical movement of the roller 12 to the brush 20, in which case the construction shown in 65 Figure 4 may be used. In this figure the stud 22 passes through the flange 30 at one end of an angle bracket which has another flange 31 projecting in the opposite direction from its other end and secured to the 70 bearing block 13.

In using power driven wringers, the clothes often become wrapped around and thereby bound to the rollers. In fact this is such a common occurrence that such devices 75 are generally equipped with arrangements for separating the rollers so that the clothes may be removed therefrom. Strippers which comprise pieces of rubber, felt or other material pressed against the rollers have been 80 tried for the purpose of preventing this objectionable feature in the operation of such wringers, but have proven to be ineffective. I have found, however, that brushes having flexible brush elements such as those referred 85 to herein are infallible in producing the result desired. It is obvious that the flexible elements of the brushes 20 prevent the clothes from being carried up over the roller 12, nor do they become caught between the 90 brush and the roller as they do when strip wipers are used. The flexibility of the brush elements provides for the vertical movement of the roller in most cases, but if desired they may be supported to rise and fall with 95 the roller as shown in Figure 4. It is also clear that the brushes 25 prevent the clothes from being carried down between the roller 11 and the board 15.

The term bristles is not limited to merely 100 animal hair, but to any equivalent substance or substances adapted to form a bristle-like structure.

While the advantages of this invention have been demonstrated and are more apparent with motor driven wringers, there is no reason for limiting its use to such devices, and in fact I intend no limitations other than those imposed by the appended claims.

110
What I claim is:

1. In a clothes wringer having parallel

rollers, a brush having a plurality of flexible brush elements, non-resilient means for holding said brush rigidly against the side of one of said rollers and parallel with the axis 5 thereof, and an inclined shelf extending from said brush.

2. In a clothes wringer having parallel rollers, a pair of brushes each having flexible brush elements, non-resilient means for holding 10 said brushes rigidly against the opposite sides of the lower roller and parallel with the axis thereof, and a pair of oppositely inclined shelves each extending from one of said brushes.

15 3. In a clothes wringer having a pair of parallel rollers, a brush having a plurality of flexible brush elements, non-resilient means for holding said brush rigidly in contact with the upper central portion of the 20 upper of said rollers and parallel with the axis thereof, a pair of other brushes each having a plurality of brush elements, non-resilient means for holding said other brushes rigidly in contact with the opposite 25 sides of the lower roller and parallel with the axis thereof, and a pair of oppositely inclined shelves each extending from one of said other brushes.

4. The combination with a frame having 30 a pair of rolls mounted therein, of a brush mounted in the frame in position to contact with the upper surface of the upper roll, and a brush contacting with the lower roll at points between the upper and lower surfaces 35 thereof.

5. The combination with a pair of rolls disposed one above the other, of a pair of op-

positely disposed brushes arranged to contact with the lower roll at points between the upper and lower sides thereof. 40

6. The combination with a clothes wringer having cooperating rolls, of means for preventing the clothes from wrapping about one of the rolls comprising a brush disposed substantially longitudinally of said roll and 45 having bristles bearing lightly on the periphery of said roll to thereby catch and throw off clothes adhering to the surface of said roll.

7. The combination with a clothes wringer 50 comprising cooperating upper and lower rolls, of means for preventing the clothes from wrapping about said rolls comprising a brush disposed longitudinally above the upper roll and having bristles projecting 55 downwardly toward and into light contact with the upper surface of said roll and longitudinally extending brushes disposed at opposite sides of the axis of the lower roll and having bristles extending into light contact with the opposite sides of said lower roll.

8. The combination with a clothes wringer having cooperating rolls, of means for preventing the clothes from wrapping about 60 the rolls comprising brushes disposed substantially longitudinally of said rolls and having bristles bearing lightly on the periphery of said rolls adapted to engage and remove clothes adhering to the surface of 70 said rolls.

In witness whereof, I hereunto set my hand this 23d day of Sept. 1919.

CHARLES C. TOMKINSON.
